UNITED STATES PATENT OFFICE.

WILLIAM L. CARD AND DAVID S. RANDOLPH, OF ST. LOUIS, MO., ASSIGNEES
TO THE CARD AUTOMATIC BRAKE COMPANY, OF SAME PLACE.

AUTOMATIC CAR-BRAKE.

SPECIFICATION forming part of Letters Patent No. 231,535, dated August 24, 1880.

Application filed March 15, 1880. (Model.)

To all whom it may concern:

Be it known that we, WILLIAM L. CARD and DAVID S. RANDOLPH, both of the city of St. Louis, in the State of Missouri, have invented a certain new and useful Improvement in Automatic Car-Brakes, of which the following is a full, clear, and exact description, reference being had to the accompanying drawings, making part of this specification.

10 Our improvement comprises an apparatus for attachment to an ordinary car and one of its trucks, and operating to apply the brakes, on the forcing inward of the draw-bar, by its impact with the draw-bar of another car when 15 the cars are at speed.

The construction and consequent operation is such that should the draw-bar be forced inward when the cars are at rest the brakes will not be applied.

20 Our invention consists in the means described and claimed for the automatic accomplishment of the above movements.

In the drawings, Figure 1 is a longitudinal section of part of a car and truck. Fig. 2 is a 25 part end view and part transverse section of the same. Fig. 3 is an under view of the same. Fig. 4 is an enlarged under view of the actuating device in a modified form. Fig. 5 is a top view of a portion of the bolster and sills 30 or floor-timbers of a car, showing the manner of attaching to them the blocks or frame on which, jointly with the floor-timbers, the hanging lever which actuates the pull-rod is supported. The frame is introduced to give additional strength. Fig. 6 is a section at *a a*,

35 Fig. 5. Fig. 7 is a side view of the automatic brake-lever, with bracket and pulley attached. Fig. 8 is a side view of the rock-shaft hanger. Fig. 9 is a perspective view of one of the bars 40 of the rock-shaft bracket. Fig. 10 is a perspective view of the push-nut which is attached to the rear end of the draw-bar to actuate the hanging lever. Fig. 11 is a perspective view of one end of a car and truck. Fig. 12 is a 45 sectional view of the fixed sleeve on the axle. Fig. 13 is an end view of same, and Fig. 14 is a perspective view of one-half of same. Fig. 15 is a perspective view of the pull-rod.

A is part of a car-body. B B are draft-timbers attached to the bottom of the same, and

between which the draw-bar C works, and to which it is connected in the usual or any suitable manner. The draw-bar C has the usual or any suitable construction. As ordinarily constructed, the draw-bar C has a screw stud 55 or bolt, which passes longitudinally through the center of the spring-pocket, and extending axially from the inner end of the draw-bar. Upon this bolt screws the push-nut D, with a curved bearing-face, *d*, bearing against the 60 sides of the U-shaped lever E, fulcrumed at its upper end to the frame or bars F F and the sills I I of the car-body.

The side bars of the frame F F are shown bolted together at the inner ends upon a distance-block, *f*, and that end fitted to the bolster G with a rabbet-notch; or it may be fitted 65 squarely against the blocking, often being placed between the sills I I where they pass over the bolster G.

70 The push-nut D, above described, is not absolutely essential, as it may be omitted and the draw-bar allowed to act directly upon the U-shaped lever E by so bending the lever E that the side next to the draw-bar shall be 75 convex.

The fulcrum-pin H passes through the sills I I of the car-body, and also the bars of the fulcrum-frame F F between them. Said pin is held in position by wooden or other suitable 80 caps H' H', attached to the outsides of the sills I I. Said fulcrum-pin passes through the upper ends of the lever E, so as to constitute its fulcrum and support.

The lever E is kept in contact with the draw-bar or push-nut D by a spring, J, or by gravity. The push-nut has two prongs, *d' d'*, which extend between the legs of the lever E, so as to prevent the nut from turning and to form a guide for the lever.

85 K is a pull-rod extending through between the legs of the lever E. This rod has a double-acting projection, *k*, upon its under side, for engagement with the lower end or bend, E', of the pendent lever E when the cars are at 90 speed. It will be seen that the hook-projections *k* of this pull-rod may be made to engage the catch E' of the pendent lever E upon either the inner or outer side thereof. The purpose of making the hook-projection *k* to 95 100

engage with and carry the lever E outward on the outward movement of the pull-rod when the cars are at speed will be made clear by the following explanation:

- 5 In starting a train of cars on leaving a station all of the draw-bars are pulled out more or less. As speed is attained the automatic mechanism hereinafter described will lower the free end of the pull-rod K, and its hook or 10 projection k will then engage the catch E' of the pendent lever E upon its inner side in such manner that the brakes will be applied whenever the draw-bar is pressed inward by 15 impact against the draw-bar of another car, so long as the cars are running at speed. On the contrary, where an extra engine is used as a pusher, as on heavy grades, the draw-bars of some of the cars are pushed inward by the force of the engine in the rear, and this forces 20 the lower end of the pendent lever E inward, so that when the automatic mechanism above referred to and hereinafter described lowers the inner end of the pull-rod K, its hooked projection k will engage the opposite or outer 25 side of the catch E' of the pendent lever E in such manner as to restrain its outward movement past the hook k, should the draw-bars happen to be stretched outward (while using the pusher-engine) by such contingency as the 30 train running through a sag in the grade after descending one grade and before ascending another in which the service of the pusher should be still required. This construction therefore effectually prevents the rear engine 35 (acting as a pusher) from setting the brakes on the cars pushed by it under any circumstances, while at the same time the forward engine (which is pulling) has complete control over the brakes upon all the cars which it 40 pulls.

The outer end of the pull-rod K passes through a bracket plate or strap, L, attached to the inner end of the brake-lever Q, and carries an adjusting-nut, K', inclosed or embraced by 45 the strap or bracket plate L. The pull-rod also passes through a sliding collar, M, which forms the inner bearing of a spring, N, whose outer bearing is against a collar, O, held in position on the rod K by means of a compressing-nut, P, 50 which gives a means for increasing or diminishing the force of spring N.

The inner side of the collar M is made convex and bears against a convex knob, l', upon the strap or bracket L. These surfaces are 55 made convex to prevent the binding of the parts when the pull-rod is in action or when the tension of the spring N is changed.

K' is a nut screwing upon the pull-rod and bearing against the inner side of the strap or 60 bracket L. The sides of the strap embrace the nut K' and prevent it turning upon the pull-rod.

It will be seen that the nuts K' and P furnish a means for lengthening or shortening 65 the pull-rod between the catch k and the nut P, or between the catch and the bearing M l',

to fit it to cars of slightly varying construction.

The strap or bracket L is hinged to one end of the automatic brake-lever Q, and the lever 70 is fulcrumed upon a stud or pin, R', upon a bracket, R, attached to one of the draft-timbers B.

The lever Q, in its preferred form, consists of two parallel bars. Between such bars, at 75 the free end, is a grooved pulley, U, around which passes a chain, T, one end of which is attached to the draft-timber B and the other end to the ordinary brake-rod V, connected by the ordinary brake mechanism with the 80 brake-beams, one of which is shown at W.

In comparing the distance moved by the draw-bar with that of the brake-beams, to arrive at the power of the brake, it will be seen that the lower end, E', of the lever E has 85 about twice the movement of the draw-bar C, as shown. This movement being communicated to the shorter end of the automatic brake-lever Q by means of the pull-rod K, the free end of the lever Q will have six times the movement 90 of the draw-bar, and as this movement is doubled upon the free end of the brake-chain T, as a result of its passing around the pulley U, the brake-rod V, to which it is attached, may be made to have twelve times the movement 95 of the draw-bar, more or less, as required. From this point—viz., the movement of the brake-rod V—the leverage is reversed in the ratio of four to one, thus giving a movement of one and one-half inch to each brake-beam 100 W for one inch movement of the draw-bar C.

We will now describe the mechanism for rendering the brake perfectly automatic.

x are lugs cast upon the inner side of the wheel X, or attached thereto in any proper 105 manner, or attached to the axle by a collar, x³, x³, bolted thereon, as shown in Figs. 4 and 12.

The part of the axle within the hub of the wheel X is somewhat reduced in diameter, so that just inside the wheel is a circumferential 110 groove, x², which gives facility for the firm attachment of the collar x³ x³ to the axle. Thus one or both of the parts x³ of the collar has a rib, x⁴, fitting in the groove x², as shown in Figs. 4, 12, 13, and 14.

To the lugs x are pivoted arms Y, carrying centrifugal blocks or weights Z at the free ends. The blocks or weights Z and their connecting-arms Y may be each in one piece. These arms are supported and have oscillatory motion on pivot-bolts x' x', which pass through eyes in the inner ends of arms Y and corresponding holes in the lugs x x on the collar x³ x³, as shown in Fig. 4, or wheels, as in Fig. 2. The bolts x' carry springs b, which tend to 125 hold the weights in contact with the axle X'. The springs b are made with a central helix surrounding the pivot-bolt x', and with projecting ends bearing, one end against the block Z and the other end against the wheel 130 or axle or object fixed to same.

It will be seen that with the described con-

struction, when the proper proportion is maintained between the weight of the blocks *Z* and the tension or strength of the springs *b*, when the car attains speed the rotary motion 5 imparted to the blocks *Z* will develop sufficient centrifugal force therein to overcome the force of the springs *b*, and the blocks will swing outward at a right angle to the axle *X'*, and that as the speed is reduced the centrifugal force 10 will diminish and be gradually overcome by the springs *b*, so that the blocks will be pressed inward and again brought into contact with the axle *X'*.

c is a collar sliding endwise on the axle and 15 revolving with it. This collar is connected to the side arms, *Y*, or blocks *Z* by toggle-links *e e*, preferably upon both sides, as seen in Fig. 3. The outward movement of the weights or blocks *Z* from the axle will draw 20 the collar *c* toward the wheel, and vice versa. This collar *c* has a circumferential groove, *g*, receiving the shoes *h* of the forked arm *i* upon the rock-shaft *j*, so that the endwise sliding movement of the grooved collar *c* will cause 25 the rocking movement of the shaft *j*. In the preferred form the forked arm *i* is attached to the rock-shaft by a joint, as shown in Figs. 1, 2, 3, and 11. This jointed connection, however, is not absolutely essential, as the rock- 30 shaft and forked arm may be made in one piece without serious detriment and their functions be performed in a satisfactory manner.

The rock-shaft *j* has an oscillating arm, *m*, 35 whose free end carries an ascending lifting-rod, *l*, that passes through an eye in the inner end, *k'*, of the pull-rod *K*. The lifting-rod *l* has a collar, *n*, by which the free end of the pull-rod is lifted when the arm *m* ascends, and 40 when the arm *m* descends the pull-rod de- scends with it until the rod reaches the catch *E'* of the lever, which then sustains the rod until again lifted by the arm *m* by means of rod *l* and collar *n*.

When the rod *K* rests on the catch *E'* the 45 rod *l* may slip down through the eye in the pull-rod without carrying the pull-rod down with it, thus avoiding strain of all the parts of the mechanism connected with the rod *K* and shaft *j*, and relieving the shoes *h* from unnecessary strain and friction. The lifting-rod *l* and its collar *n* are not, however, absolutely 50 essential, as both might be dispensed with by a slight modification. For instance, the arm *m* in its upward movement might be brought 55 in direct contact with the under side of the pull-rod, near its free end, so that it would raise and lower the free end *k'* of the pull-rod, substantially in the same manner as the 60 preferred mechanism above described.

The rock-shaft *j* is supported at one end by a *V*-formed hanger, *o*, whose ends are attached to the body of the car, (see Fig. 2,) and whose middle or lower part is bent into an eye, *p*, to 65 give a suitable bearing to the rock-shaft. (See Fig. 8.) The other end of the rock-shaft is

supported on a spider-bracket, which consists of two *V*-formed bars, *q* and *r*, attached to the face of the cross-timbers of the truck *S'*. The bearing-eye *q'*, Fig. 9, of the upper member, *q*, 70 is turned down, lapping over the upturned bearing-eye *r'* of the lower member, *r*, so as to form a lock by the weight of the shaft in its bearing. This lock is also maintained by means of the collars *t t*, as seen in Figs. 1 and 75 3. The lower member, *r*, forms the strut of the bracket-frame, and the upper member, *q*, the stay. The collars *t t* at each side of the bearing *q' r'* also prevent endwise movement 80 of the rock-shaft *j*. The arm *m* is at the end of the rock-shaft supported upon the car-body by means of the hanger *o*. It will follow that this end of the rock-shaft will partake of all the vertical and lateral movements of the car-body. The other end of the rock-shaft is supported 85 from or upon the truck by means of the above-described spider-bracket *q r*, and this end therefore partakes of all the movements of the truck.

It will be seen that the bearing *q' r'* of the 90 bracket forms the central point of oscillation for that end of the rock-shaft to which is attached the forked arm *i*, to which movement is imparted by the grooved collar *c* by means of its endwise movement, induced by the centrifugal blocks *Z*; also, that the eye *p* of the hanger *o*, which is attached to the car-body, is the central point of oscillation for that end of the rock-shaft which carries the oscillating arm *m*, whose office is to raise and lower the 100 pull-rod out of and into engagement with the lower end, *E'*, of the pendent lever *E*; also, that the pull-rod, being carried and supported entirely from the car-body, must, as a natural consequence, partake of all the movements of 105 the car-body.

It will now be seen that the movements of the rock-shaft, caused by the sliding collar *c* by means of the forked arm *i*, will be certain and reliable, because the center of oscillation 110 at *q' r'*, above set forth, for all these parts partake of all the movements of the truck; and also that the result of the vibrating movements of the arm *m* of the rock-shaft will be certain and reliable, because the center of oscillation 115 for this part of the mechanism, at *p*, as above set forth, partakes of all the movements of the car.

To obtain best results with the least wear and tear it is absolutely necessary that the 120 bearings or supports for the rock-shaft should be attached as above described—one to the truck and the other to the car-body. Otherwise the effect is modified by the amount of load upon the car, producing a greater or less depression upon the body of the car by depressing the springs in the truck; also, by the side lurch of the body upon the hangers in the truck upon which it is carried; also, by the truck being elevated at one end by inequalities in the 125 surface of the track and by curvature of the track. A practical result may be attained, 130

however, with our mechanism by supporting both ends of the rock-shaft upon the truck in any suitable manner; but it is less satisfactory in many respects.

- 5 We do not confine ourselves to the form of bracket *q r* or hanger *o* shown to support the rock-shaft, as they may be varied indefinitely as exigencies may arise to conform to the construction of various cars or for economy in 10 weight of material, the essential characteristic being that they support the rock-shaft from the truck at one end and from the car at the other, or in any manner so as not to interfere with its duty of controlling the vertical movement of the inner end, *k'*, of the pull-rod *K*.
 15 The operation of the various parts having been described in detail, it is unnecessary to give a general description of same. We will, however, say that when the cars are not running at least at a moderate speed, the double-hooked projection *k* of the pull-rod *K* is held above and out of engagement with the catch *E'* of lever *E*, so that the pull-rod is not affected by the inward and outward movement 20 of the draw-bar and lever *E*. When, however, the draw-bar is extended and the cars at a moderate speed, the inward movement of the draw-bar applies the brakes, and they remain set until the draw-bar is again moved outward.
 25 30 This operation of applying and releasing the brakes may be repeated at the pleasure of the engine-driver until the train comes to a full stop or the speed has been so reduced that the tension of the springs *b b* will overcome 35 the centrifugal force of the blocks *Z Z*.

It will be understood that the cars may be backed without setting the brakes, because when the draw-bar is thereby forced inward the projection *k* on the pull-rod will be above 40 the bar *E'*. Should sufficient speed be attained while backing to lower the catch *k* into en-

gagement with the catch-bar *E'* it will engage it on the outer side, and thus effectually prevent the possibility of setting the brakes, as above set forth in describing the action of a 45 pusher-engine.

We claim herein as new and of our invention—

1. The combination of draw-bar *C* and push-nut *D* with the pendent lever *E*, said push-nut having prongs or projections sliding in connection with said pendent lever, as and for the purpose set forth. 50

2. The lever *Q*, pivoted to the supporting-bracket *R*, and carrying on its outer end the grooved chain-pulley *U*, and having on its inner end a bracket-plate, *L*, in the described combination with the collar *M* and rod *K*. 55

3. The lugs *x x*, cast upon the inner side of a car-wheel, in combination with the pivot-bolts *x' x'* and centrifugal blocks *Z Z*, with side arms or projections, *Y Y*, substantially as set forth. 60

4. The combination of the draw-bar *C* and push-nut *D* with the pendent lever *E* and spring *J*, as shown and described. 65

5. The pull-rod *K*, having adjustable nut *K'* and double-acting projection *k*, for the purpose shown and described.

6. The combination of the draw-bar *C*, pendent lever *E*, and pull-rod *K*, for the purpose shown and described. 70

7. The combination of the spider-bracket *q r* and hanger *o* with the rock-shaft *j*, for the purpose of supporting said rock-shaft from the truck and car, as shown and described. 75
